UNITED STATES PATENT OFFICE.

DOANE POWELL, OF OMAHA, NEBRASKA.

DESIGN FOR AN ELECTRIC-LIGHT OR GAS FIXTURE.

49,492.

Specification for Design.

Patented Aug. 8, 1916.

Application filed February 7, 1916. Serial No. 76,869. Term of patent 3½ years.

To all whom it may concern:

Be it known that I, DOANE POWELL, a citizen of the United States, residing at Omaha, in the county of Douglas and State of Nebraska, have invented a new, original, and ornamental Design for Electric-Light and Gas Fixtures, of which the following is a specification, reference being had to the accompanying drawing, forming part thereof.

The figure is a perspective view of an electric light and gas fixture showing my new design.

I claim—

The ornamental design for an electric light or gas fixture as shown.

DOANE POWELL.
